UNITED STATES PATENT OFFICE

130,252

DESIGN FOR AN EDUCATIONAL LAPBOARD

Melvin T. Oakes, Greensboro, N. C.

Application March 7, 1941, Serial No. 99,411

Term of patent 14 years

To all whom it may concern:

Be it known that I, Melvin Talmage Oakes, a citizen of the United States, residing at Greensboro, in the county of Guilford and State of North Carolina, have invented a new, original, and ornamental Design for an Educational Lapboard, of which the following is a specification, reference being had to the accompanying drawings, forming part thereof.

Fig. 1 is a top perspective view of an educational lapboard, showing my new design;

Fig. 2 is a plan view of the left half thereof; and

Fig. 2A is a plan view of the right half thereof.

I claim:

The ornamental design for an educational lapboard, as shown.

M. T. OAKES.
